Primary Examiner — Elizabeth A. Albert*Assistant Examiner* — Kelley Donnelly(74) *Attorney, Agent, or Firm* — Andrus, Sceales, Starke & Sawall, LLP(57) **CLAIM**

The ornamental design for a lounge seating, as shown and described.

DESCRIPTION

FIG. 1 is a perspective view of a first embodiment of a lounge seating;

FIG. 2 is a front elevation view thereof;

FIG. 3 is a right side elevation view thereof, wherein the left side elevation is a mirror image;

FIG. 4 is a rear elevation view thereof;

FIG. 5 is a top plan view thereof;

FIG. 6 is a bottom elevation view thereof;

FIG. 7 is a perspective view showing a second embodiment of a lounge seating;

FIG. 8 is a front elevation view thereof;

FIG. 9 is a right side elevation view thereof; the left side elevation view being a mirror image;

FIG. 10 is a rear elevation view thereof;

FIG. 11 is a top plan view thereof; and,

FIG. 12 is a bottom plan view thereof.

The broken lines showing is included for the purpose of illustrating environment of the design and forms no part of the claimed design.

The break lines shown in FIGS. 1, 2, 4, 5, 6, 7, 8, 10, 11, and 12 are not part of the claimed design and represent that no particular length is claimed.
